(57) **CLAIM**

The ornamental design for an implant delivery apparatus, as shown and described.

DESCRIPTION

FIG. 1 is a front, top, and left side perspective view of an implant delivery apparatus of our design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines shown in the figures are included for the purpose of illustrating portions of the implant delivery apparatus and form no part of the claimed design.
